UNITED STATES PATENT OFFICE.

LAWRENCE F. OTTEN, OF NEWPORT, KENTUCKY.

BUCKLE FOR PERSONAL WEAR.

1,382,737.

Specification of Letters Patent. Patented June 28, 1921.

Application filed January 24, 1920. Serial No. 353,832.

To all whom it may concern:

Be it known that I, LAWRENCE F. OTTEN, a citizen of the United States, residing at Newport, in the county of Campbell and State of Kentucky, have invented certain new and useful Improvements in Buckles for Personal Wear, of which the following is a specification.

My invention relates to buckles, and particularly to those used upon belts for personal wear.

The object of my invention is to provide a buckle of efficient and economical construction which is adapted to securely grasp and hold a belt upon the wearer at any point without the necessity of weakening the belt by perforations to receive the ordinary tongue of a buckle.

My invention consists in the construction, combination and arrangement of parts as herein set forth and claimed.

In the drawing which serves to illustrate a preferred construction of my invention;

Figure 1 is a front view of the buckle with the ends of a belt attached thereto;

Fig. 2 is an edge view of the same;

Fig. 3 is a longitudinal section on the line 3—3 of Fig. 1;

Fig. 4 is a rear view thereof; and

Fig. 5 is a perspective view of a fluted cam.

My improved buckle comprises a concavo-convex plate 1, having rearwardly extended flanges 2 and 3 at its upper and lower edges respectively, said flanges being preferably provided with tapering surfaces 4 and 5 respectively at their ends and being curved or recessed between the ends to form extensions 6 and 7 respectively. A pin 8 is mounted in openings 9 in extensions 6 and is held in position by heads 10 formed upon its ends. A sleeve 11 is mounted on said pin and a belt attaching loop 12 is pivotally mounted on said pin between said sleeve and extensions 6. One end of belt 13 is suitably connected to said loop.

Fluted cam 14 is provided upon its concave side near one edge thereof with a bearing sleeve 15 suitably formed thereon, and a pivot pin 16 is mounted therein, and projects from each end thereof to enter holes 16 in extension 7, after which heads 18 are formed thereon to hold said pivot pin in place so that said ridged cam is pivotally mounted thereon, with its ridged side disposed toward the rear side of the plate and

with its free edge 19 extending inwardly toward the center of plate 1, as clearly shown in Fig. 3.

The flanges 2 and 3 are cut away between their ends to form the extensions 6 and 7 and to permit the plate to receive the double lap of the trouser opening and to fit snugly thereagainst.

When the buckle has been constructed and assembled and connected to one end of the belt as above described, the other end of the belt is inserted between the plate and cam until the proper tightness of the belt upon the person has been obtained. The tension of the belt drawn across the concave surface of the plate and between said plate and cam will firmly grasp and hold the belt in the desired adjusted position.

Heretofore buckles having tongues to engage perforations in the belt did not permit of fine adjustment of the belt to any position desired and frequently additional perforations had to be made by the user. By the use of my improved buckle all perforations are dispensed with, thereby adding to the beauty and life of the belt and at the same time permitting of a greater range of adjustment to any position desired, depending upon the size of the user or upon the degree of tightness to which he wishes it adjusted.

It will be apparent that my invention is capable of some modification without departure from its scope or spirit, as for instance, while I have shown cam 14 provided with ridges 20 to engage and grip the belt to prevent slipping thereof, any other roughened or raised surface may be used in lieu thereof.

What I claim is new and desire to secure by Letters Patent is:

1. In a belt buckle for personal wear, a concavo-convex plate having rearwardly extending flanges, a pin mounted in said flanges, a sleeve on said pin, a belt loop pivotally mounted on said pin between said sleeve and said extensions respectively and a cam having pointed ridges, and pivotally mounted in the other end of said extensions respectively and adapted to receive the other end of said belt between said cam and said plate whereby said plate is adapted to be held upon the user in any desired position, substantially as set forth and for the purposes specified.

2. In a belt buckle for personal wear, a

plate having laterally extending flanges, extensions on said flanges cut away at their ends to permit the plate to receive the double lap of the trouser opening and fit snugly thereagainst, a belt loop pivotally connected to two of said extensions and a ridged cam pivotally connected to the other two of said extensions, substantially as set forth and for the purposes specified.

3. In a belt buckle for personal wear, a 10 cam having a convex engaging surface provided with a plurality of sharp ridges, concave surface, a sleeve fixed to said concave surface near one edge of said cam and a pivot in said sleeve, substantially as set forth and for the purposes specified.

LAWRENCE F. OTTEN.
